JAMES B. HICKS, OF BRANSON, MISSOURI.

SUBSOIL-PLOW.

No. 816,548.

Specification of Letters Patent.

Patented March 27, 1906.

Application filed January 2, 1906. Serial No. 294,207.

To all whom it may concern:

Be it known that I, JOSEPH B. HARRIS, a citizen of the United States, residing at Branson, in the county of Taney and State of Missouri, have invented a new and useful Subsoil-Plow, of which the following is a specification.

This invention relates to improvements in subsoil attachments to plows, and has for its object to produce a simply-constructed device of this character which may be readily adapted to the various construction of turning-plows without structural changes in the plows or in the attachment.

With these and other objects in view, which will appear as the nature of the invention is better understood, the invention consists in certain novel features of construction, as hereinafter fully described and claimed.

In the accompanying drawings, forming a part of this specification, and in which corresponding parts are denoted by like designating characters, is illustrated the preferred form of the embodiment of the invention capable of carrying the same into practical operation, it being understood that various changes in the form, proportion, and minor details of construction may be resorted to without departing from the principle or sacrificing any of the advantages of this invention within the scope of the appended claims.

In the drawings, Figure 1 is a side elevation of the improved device with the moldboard in section and one of the handles removed. Fig. 2 is a plan view of a plow with the improvement attached. Fig. 3 is an enlarged perspective detail illustrating the construction of the subsoil-standard guides. Fig. 4 is an enlarged perspective detail of the means for adjusting the subsoil-plow standard.

The improved attachment comprises in general a subsoil-plow moldboard attached to a vertical standard, a radius-bar for connecting the subsoil-plow standard to the turning-plow, spaced guide members embracing the subsoil-plow standard and having means for attachment to the turning-plow and means for adjusting the subsoil-plow standard and its moldboard vertically to control the depth to which the subsoil-plow will operate and also to elevate the same above the ground when not in use.

The moldboard of the turning-plow is represented at 10, the landside at 11, and the

beam at 12, the latter bolted or riveted at its 55 foot 13 to the landside, as at 14. The left-hand handle 15 is secured at the lower end to the plow by one of the rivets or bolts 14, while the right handle 16 is riveted or bolted at 17 to the moldboard 10, the two handles 60 connected to each other by transverse stay-bolts 18, spaced apart, as shown. Braces 19 20 are bolted at one end at 21 to the beam and diverge and extend rearwardly to one of the transverse stay-rods 18, to which they 65 are secured at their rear ends.

The subsoil-moldboard is represented at 22 of the usual or any desired form and connected to a vertical standard 23, the latter having a plurality of spaced apertures 24. The 70 standard 23 passes through spaced guards 25 26, formed of U-shaped rods and coupled to two of the transverse stay members 18. Pivoted at the ends at 37 38, respectively, to the beam 12 and the subsoil-plow standard 75 23, is a radius-bar 39. Pivoted to the bolt 21 by which the braces 19 20 are connected to the beam, is a lever 27, extending rearwardly and movably connected by a bolt 28 to one of the apertures 24 of the standard 23. Connected at 29 to the landside 11 is a supporting standard 30, extending upwardly and provided with a plurality of spaced apertures 31. The lever 27 is provided with a keeper 36, through which the supporting standard 80 85 or bar 30 passes, and pivoted at 32 to the lever is a lock-bar 33, leaving a handle 34 at one end adjacent to the handle end 35 of the lever 27 and with the other end bent laterally and passing through an aperture in the 90 keeper 36 and into one of the apertures 31 in the bar 30. By this means the operator can very quickly adjust the subsoil-plow to operate at any required depth or to elevate the same above the lower line of the landside 11 95 and moldboard 10 when not required.

The radius-bar 39 holds the standard 23 and its moldboard 22 firmly in position and effectually resists all tendency to rearward movement. The pivot-bolts 21 28 and lever 100 27 effectually prevent any tendency to forward movement of the upper end of the standard, while the guard members 25 26 hold the standard from lateral movement. The spaced apertures 24 provide for the vertical adjustment of the subsoil-plow beam, so that the depth of cut may be increased or decreased, as required.

Having thus described the invention, what is claimed is—

1. The combination with a plow including a moldboard, landside, beam and diverging handles connected by spaced stay members, of a subsoil - moldboard having a vertical standard, guard members connected to said stay members and embracing the standard, a radius-bar movably connecting said standard to the plow, and means connected to the plow for adjusting the standard and its moldboard and maintaining the same in adjusted position.
2. The combination with a plow including a moldboard, landside, beam and diverging handles connected by spaced stay members, of a subsoil - moldboard having a vertical standard, guard members connected to said stay members and embracing the standard, a

radius-bar movably connecting said standard to the plow, a supporting-bar rising from the landside and provided with a plurality of spaced apertures, a lever pivoted at one end to the beam and adjustably coupled to said standard and provided with a keeper embracing said supporting-bar, and a locking member movably connected to said lever and with one end extended laterally for engagement one at a time with the aperture in the supporting-bar.

In testimony that I claim the foregoing as my own I have hereto affixed my signature in the presence of two witnesses.

JOSEPH B. HARRIS.
